UNITED STATES PATENT OFFICE

172,473

TABERNACLE

Leo R. Le Tang, Cincinnati, Ohio

Application December 29, 1953, Serial No. 28,276

Term of patent 14 years

(Cl. D29—23)

To all whom it may concern:

Be it known that I, Leo R Le Tang, a citizen of the United States and a resident of Cincinnati, in the county of Hamilton and the State of Ohio, have invented a new, original, and ornamental Design for a Tabernacle, of which the following is a specification, reference being made to the accompanying drawing, forming a part thereof.

Fig. 1 is a front perspective view of a tabernacle, showing my new design.

Fig. 2 is a rear perspective view of said tabernacle.

I claim:

The ornamental design for a tabernacle, substantially as shown.
